SALES PROMOTION APPARATUS

Rolla G. Sievers, Valparaiso, Ind.

Application June 17, 1940, Serial No. 341,019

1 Claim. (Cl. 101—69)

My invention relates to improvements in a sales promotion system and apparatus therefor and it more especially consists of the features pointed out in the annexed claim.

The purpose of my invention is to provide cooperating apparatus that will promote the sale of merchandise; that will rapidly stimulate the movement of standard or special goods; that will encourage the desire to buy; that at all times will give an equivalent for every coin that is inserted in a cooperating vending machine; that for each coin inserted a ticket or coupon is delivered which on its face indicates its redemption value exchangeable for certain indicated goods of the merchant of the same retail value or cash as the coin which was inserted; that will provide a single prearranged coupon in a selected group that will for the same denomination of the coin inserted entitle the holder to exchange it for the merchant's goods having a retail value at least twice that of the coin inserted into the vending apparatus; that will provide for the recurrence of a special coupon in regular or irregular sequence as desired; and that also will adapt my system to the disposal of goods from conventional vending machines and with each article delivered will also supply a coupon redeemable for the same value as the coin which was inserted in the machine. All coupons will bear a local advertisement and that of any sponsoring concern whose participation, independently of the merchant's profits, through the sale of his goods, is of exceptional advertising value.

The mechanism is susceptible of almost unlimited changes. In one form it includes pre-printed tickets, regular ones with a special one separating groups of regulars, or any desired form of printing mechanism which, after the recurrence of regular imprints on the next operation of the machine, will print the next coupon as a special and will repeat the sequence over and over. The web or tape on which the tickets are printed may come in the shape of a roll or they may be stacked in accordion fashion. In any event severing mechanism is provided to cut the tape into individual coupons for each coin inserted.

With these and other ends in view I illustrate in the accompanying drawing such an instance of adaptation as will disclose the broad idea of the invention. I do not, however, intend to limit myself to the specific details shown thereon and described herein.

Fig. 1 is a diagrammatic perspective of the cooperating parts showing the unlocking, feed-

ing, impressing, and severing features of my system.

Fig. 2 is a sectional elevation showing the relation of the tape and the knife for cutting the tape into coupon lengths.

Fig. 3 is a transverse section of the punch or impressing feature.

Fig. 4 is an elevation showing the locking and unlocking features.

10 Fig. 5 is an elevation of the means for operating the impressor.

In the practice of my invention I may use whatever equivalents of mechanism or alternatives of operation that the peculiarities of varying conditions may demand without departing from the broad spirit of the invention.

The simplest form of my apparatus includes the following structure with which a preprinted coupon web or strip 1 is used. It includes a 20 lower disk 3 and an upper disk 2. The two disks are interconnected by gears 4. The web passes through between the disks. The upper one does the feeding and if desired it may have a knurled or serrated face to prevent slipping of the web. 25 The lower disk may be adjusted vertically to secure any desired tension on the web (not shown).

The upper or feed disk has a shaft 5 on which there is mounted a ratchet 6. This shaft also 30 has mounted thereon a worm 7 that meshes with a worm gear 8 which controls the impressing or punching operation. At the end of the shaft there is a rock arm 9, movably loosely on the shaft, which carries a pawl or dog 10 that engages the ratchet 6. The rock arm is connected by a link 11 pivoted to it between the shaft and the pawl. It is connected to an extension 12 of the hand lever 13 which is pivoted on a spindle 14 for movement between a rear stop 40 15 and a forward stop 16. A coil spring 17 is on this spindle. One end of it is secured to a stationary bearing 18 and the other end to the operating handle. The tension of this spring returns the handle from its extreme forward to 45 its extreme rearward position. The handle has a short crank extension 19 that is connected by a link 20 to a bell crank 21 suitably pivoted to which another link 22 is attached. This link operates the severing knife 23 which is pivoted beneath the web. It cooperates with a front edge of a supporting plate 24 positioned above the web. The action of the pivoted knife is similar to the action of an ordinary pair of shears.

55 The knife is timed for action just at the end

of the feeding period. The severed ticket or coupon 25 may drop into any kind of a receptacle.

The shaft 5 on which the feed wheel, the worm and ratchet are attached positions the worm 7 over a worm gear 8 with which it meshes in any desired ratio so that the gear may make one revolution for each ten revolutions of the worm or in any other ratio. There is a supporting spindle 26 for the gear. At its outer end there is a trip arm 27 which actuates a punch link 28 that is fulcrumed about mid-way of its length. The other end of this arm is connected by a link 29 to a vertically moving punch or impressor 30. This is normally held in its lowered or inactive position by a spring 31 in cooperation with a limiting stop 32. The impressor 30 has vertical movement in a downward projection of a guide plate 33 on the underside of the web. A cooperating plate 34 is placed directly above the web so that the web is supported while the impression is being made.

Any desired form of conventional coin release may be used to unlock the operating lever 13 which on its return stroke becomes automatically locked until another coin is inserted. The severing and impressing means may be motor operated (not shown) under the control of an operating switch.

My device is not complicated. There are not many basically necessary cooperating parts. The web or tape may be stored in any desired manner. It is passed through between the two disks in such relation that the beginning or front end of a preprinted coupon would be under the center of the feed wheel from which point it will travel forward under the movement of the wheel and the hand lever 13 until the arc of movement has been completed. This may approximate 60 degrees more or less. It will represent practically $\frac{1}{6}$ of the circumference of the feed disk which means that the ratchet will have approximately six teeth in its circumference.

The circumferential travel of the disk 2 and the inter-related travel of the disk 3 to the pre-arranged spacing of the imprint areas on the tape 1 may be adjusted in order to adapt the two speeds to each other, especially in relation to the starting point of the feed wheel 2 to the beginning of an imprinted area on the tape. Any conventional form of clamping screw adjustment, between the disk 2 and the toothed gear 4, may be employed (not shown). Ordinarily such adjustment may not be needed as the starting point of the feed wheel 2 in relation to the beginning of an imprinted area may be set in coordination with the position of the tape between the wheels 2 and 3 and to the position of the severing knife 23.

The operation of my device simply involves the deposit of a coin 36 through a chute 37 which releases the hand lever 13. The coin release comprises a pivoted hook-ended lever 38 pivoted at 39. It has an upstanding projection 45 that is beveled at its upper end at 40 to engage the coin 36 and to prevent it falling until the magnet 41 in circuit 42 draws the bevel 40 and the projection 45 toward it and releases the hook-ended lever 38 from the pin 43 thus freeing the hand lever 13. The circuit 42 has an insulated portion 44 against which the coin 36 rests,

the other side of the circuit being closed through the projection 45 which is acted upon the magnet 41.

The movement of the hand lever to its full down and up stroke separates the preprinted coupon from the web and delivers it to the customer. At the end of each tenth or other sequence a special or double value coupon will be delivered and it will be identified with an impression "S" or other insignia, by the impressor 30. The momentary impressing and the momentary severing are both performed just before the hand lever is returned to its upward limit. All the operating parts may be supported on any kind of frame assembled in any desired cabinet.

The coupons may be preprinted as desired. They may carry local or general advertising. Regardless of the value of the coin to which the machine is adjusted for a specific user or merchant, every regular coupon that is delivered by the machine entitles the holder to have it redeemed for the same value as the coin that was inserted, in goods of the local merchant or in cash. Every special coupon may similarly be redeemable for a value at least double that of the regular coupons in merchandise but not in cash. The coupons aside from advertising matter may have printed thereon a notice approximating the following:

"This coupon has a redemption value in cash or goods, only at the store advertised hereon, of the same value as the coin which was inserted. Notice. Any coupon having an identification "S" or otherwise on it, entitles the holder to exchange it, only at the store advertising hereon, for goods at least to double the value of the coin inserted."

What I claim is:

In a sales promotion apparatus of the class described adapted to feed a tape or web having lengthwise preprinted duplicate ticket indicia thereon which includes a pair of feed wheels adapted to engage the tape therebetween, interconnected gears between the wheels, a feeding shaft attached to one of the wheels, a ratchet on such shaft, means for manually actuating the ratchet to intermittently move the wheels to feed the continuous length tape the distance of a single preprinted ticket for each movement of the ratchet, a knife for severing the tape between each pair of preprinted tickets, means for actuating the knife synchronously with each movement of the ratchet, a worm on the feeding shaft, a worm gear intermeshing with said worm, a spindle for the worm gear, a trip on said spindle, indenting means positioned beneath the tape said means comprising a supporting plate above the tape directly opposite the impressing means, means for actuating the impressor by said trip once only for a predetermined number of ratchet movements during a cooperating movement of the circumference of the feed wheels to include a predetermined length of single tickets so that after each group is detached from the tape a single ticket bearing the indented identifying mark is severed the time of such indenting and severing being dependent on the ratio of the worm to the worm gear, whereby a single indented ticket of double redemption value is delivered after each group of unindented half value redemption tickets.

ROLLA G. SIEVERS.
